Primary Examiner — Mark Goodwin(74) *Attorney, Agent, or Firm* — Wood Herron & Evans LLP(57) **CLAIM**

The ornamental design for a rubber-tired road roller, as shown and described.

DESCRIPTION

FIG. 1 is a right front perspective view of a rubber-tired road roller showing our new design;

FIG. 2 is a left front perspective view of the rubber-tired road roller shown in FIG. 1;

FIG. 3 is a right rear perspective view of the rubber-tired road roller shown in FIG. 1;

FIG. 4 is a left rear perspective view of the rubber-tired road roller shown in FIG. 1;

FIG. 5 is a front elevation view of the rubber-tired road roller shown in FIG. 1;

FIG. 6 is a rear elevation view of the rubber-tired road roller shown in FIG. 1;

FIG. 7 is a right side elevation view of the rubber-tired road roller shown in FIG. 1;

FIG. 8 is a left side elevation view of the rubber-tired road roller shown in FIG. 1;

FIG. 9 is a top plan view of the rubber-tired road roller shown in FIG. 1; and,

FIG. 10 is a bottom plan view of the rubber-tired road roller shown in FIG. 1.
